UNITED STATES PATENT OFFICE.

ERIK S. HAGEN, OF CHICAGO, ILLINOIS, ASSIGNOR OF ONE-HALF TO CLAUS F. ROBERG, OF SAME PLACE.

ROTARY STEAM-ENGINE.

SPECIFICATION forming part of Letters Patent No. 593,375, dated November 9, 1897.

Application filed January 22, 1897. Serial No. 620,171. (No model.)

To all whom it may concern:

Be it known that I, ERIK S. HAGEN, a subject of the King of Sweden and Norway, residing at Chicago, in the county of Cook and State of Illinois, have invented certain new and useful Improvements in Rotary Steam-Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to that type of rotary steam-engines in which power is applied by the impact of the steam upon a rotary part; and its object is to provide a construction whereby all of the steam-pressure becomes available, the steam being applied to a succession of motors which drive a shaft common to all, so that the exhaust may be at a pressure as low as desired.

The details of the construction whereby the object of the invention is attained are fully set out in the following specification.

In the drawings, Figure 1 is a central longitudinal vertical section of the engine. Fig. 2 is a side elevation of the same. Fig. 3 is a sectional view on the line 3 3 of Fig. 1. Fig. 4 is a sectional view on the line 4 4 of Fig. 1. Fig. 5 is a detail on the line 5 5 of Fig. 5. Fig. 6 is details of the construction of the rotating parts. Fig. 7 is an elevation of the disk face of one of the rotating parts, and Fig. 8 is a detail section on the line 8 8 of Fig. 1.

The body of the engine is cylindrical in form and is securely bolted to a bed-plate 15 and is built up of a plurality of cylindrical sections, as shown, six in number and designated 9, 10, 11, 12, 13, and 14, all securely bolted together. The first section 9 has a somewhat commodious annular channel 40 formed in its inner face to serve as a steam-chest, and the steam-pipe 23 enters this chest, which is closed or covered by the next section 10. Section 10 is provided with a plurality of steam-ducts 10^a, as shown, two in 45 number and diametrically disposed. These ducts pass obliquely through the section, 50

bearing in the direction in which the moving part of the engine is desired to rotate.

The remaining sections of the body of the engine, 11, 12, 13, and 14, are substantially 55 alike, each comprising a disk having an annular flange which abuts against the preceding section, whereby a succession of chambers are formed, within each of which is located a disk, as 17, 18, 19, and 20, fixed upon 60 so as to rotate with the shaft 16, which passes axially through the body of the engine, the several sections of which are centrally apertured for its accommodation. The first rotating disk 17 is in frictional contact with the 65 face of section 10 of the body of the engine, and its contacting face is provided with a plurality of recesses 17^a, as shown, three in number, so arranged as to register with the steam-ducts 10^a and also with the exhaust-recesses 10^b, formed in the face of section 10 intermediate of the steam-ducts. The disk 17 being of less diameter than the chamber within which it rotates and the recesses 10^b extending radially beyond its periphery, the 70 steam escapes from the recesses 17^a through the recesses 10^b over the edge of the disk 17 into the chamber within which this disk rotates and passes thence through suitable steam-ducts 11^a in the disk portion of section 80 11. These ducts are of any desired number and are directed obliquely, being inclined in the direction of rotation. The next rotating part comprises a disk 18 of less diameter than the disk 17 and having a plurality of radial 85 slots setting in from its periphery, these slots being oblique to its axis. Within these slots are set blades 24, the exposed portions of which are preferably curved and which have their ends 24^a turned down to form an outer 90 periphery facing for the disk, the extreme end of one blade bearing against the back of the adjacent blade. The angle at which these blades are set is such that their faces are substantially perpendicular to the line at which 95 the steam enters through the ducts 11^a. The blades 24 are secured to the disk 18 by having the edges of their shanks cut so that lugs 24^b may be turned backwardly to fit within suitable recesses formed within the faces of 100 the disk. The impact of the steam-jets entering through the ducts 11^a upon the blades

24 imparts power to the disk, and the steam passes through between the blades into the chamber within which the disk rotates and escapes therefrom through similar ducts 11^a 5 in the disk portion of section 12 of the body of the engine. The succeeding rotating parts 19 and 20 are identical in construction with the disk 18 and are supplied with steam in the same manner, and the final exhaust is by 10 means of a pipe 25, which is preferably located at the bottom of the engine, so as to carry away the water of condensation. As already 15 stated, the number of sections of which the body of the engine is composed, and of course of the rotating disks, may be varied, and whether increased or diminished from the number shown the exhaust-pipe 25 is always located in the last section.

As the engine is driven at an exceedingly 20 high speed, it is desirable that the shaft 16 be flexible, and to this end I show it as composed of two sections 16 16^a, the latter being journaled in double floor-hangers 22, so as to prevent its vibration. The two sections of 25 the shaft are united by means of a sleeve 27, fixed upon the end of section 16, and being of slightly greater bore than the diameter of the end of section 16^a, which enters it. A pin 27^a unites the sleeve 27 with the shaft-section 16^a, being fixed in the sleeve and passing loosely through a transverse aperture in the shaft, which flares at both ends, so that any vibration of the shaft-section 16 is not transmitted to the shaft-section 16^a. The 35 other end of the shaft is journaled in a block 28, which is mounted upon a flexible stud-shaft 29, fixed in the hanger 21. As the steam-pressure is applied to the rotating disks in such manner as to give the shaft an 40 end thrust, I interpose at the ends of the shaft bearing-blocks 29^a and 30, and at the extreme ends of the shafting adjusting-screws 31 32 are placed.

Suitable packing is interposed between the 45 hubs of the rotating disks and the disk portions of the sections of the body of the engine, with which they co-operate, so as to prevent the escape of steam, and in order to provide for the vibration of the shaft I use 50 in connection with this packing-blocks 26, which are free to slide upon the fixed part of the engine-body. Any form of elastic packing may be used, so as to insure a tight joint at both ends of the hub.

55 At 33 is shown an oil-duct, which may of course be repeated in each one of the sections or replaced by any other suitable means for delivering oil to the bearings.

The several rotating disks may, if desired, 60 be all alike, and may be either of the type shown at 17 or of the type shown at 18.

It will be seen that the pressure of steam 65 is reduced step by step, and that the available pressure upon each disk is the difference between the pressure at which the steam enters the chamber in which the disk is located and the pressure at which it leaves that cham-

ber, so that the aggregate pressure applied to the rotating parts of the engine, assuming that the engine exhausts at zero, is the service pressure less the loss in friction due to the passage of the steam through the ducts and in radiation. 7c

I claim as my invention—

1. The combination with a fixed casing having apertured ends, of a rotatable laterally-movable shaft projected loosely through such apertures, a disk within the casing and fixed upon such shaft and having radial impact-faces oblique to the direction of movement, 80 packing-plates mounted upon the shaft and having steam-tight connection therewith and being in sliding contact with the inner faces of the walls of the casing and covering the apertures therein, a steam-duct entering the 85 casing and being directed toward the impact-faces, and an exhaust-passage leading from the casing.

2. The combination with a casing having its end walls apertured, a rotatable jointed 90 shaft passing loosely through such apertures and being in some of its parts flexible, a disk within the casing and fixed upon the shaft and having radial impact-faces, an induction-passage directed toward the faces, and an exhaust-port, of packing-plates mounted upon the shaft and being in sliding contact with the inner faces of the walls of the casing and closing its apertures, and having steam-tight 95 connection with the shaft, substantially as 100 described and for the purpose specified.

3. The combination with a fixed casing having apertured ends, a rigid rotatable shaft, 105 16, located loosely within such apertures, a shaft, 16^a, journaled in fixed bearings and having a universal-joint connection with the shaft, 16, a flexible shaft, 29, secured in a hanger at the opposite end of the casing and being jointed to the end of the shaft, 16, a disk within the casing and fixed upon the 110 shaft, 16, and having radial impact-faces, an induction-duct directed toward the impact-faces, and an exhaust-port, of packing-plates interposed between the disk and the walls of the casing and having steam-tight connection 115 with the shaft, 16, and sliding contact with the inner surfaces of the casing-walls, substantially as described and for the purpose specified.

4. The combination with a rotative shaft-section, journal-boxes for holding such shaft-section against lateral vibration, a rigid shaft-section, 16, connected with such first-mentioned shaft-section by a universal joint, a flexible stud-shaft and means for supporting the same, a journal-box mounted upon the outer end of the stud-shaft for receiving the end of the shaft-section, 16, and means for applying power to such last-mentioned shaft-section to rotate it. 120

5. The combination with a fixed casing having induction and discharge ports, and apertured ends of rotative disks within the case, and having radial concave blades oblique to 125 130

the direction of rotation, partitions crossing the interior of the casing so as to provide a separate compartment for each disk and having apertures in alinement with the apertures 5 of the ends of the casing, steam-passages through such partitions so disposed as to discharge upon the concave faces of the blades, a shaft, 16, for carrying the disks and in fixed relation thereto, and passing loosely 10 through the casing, packing-plates fixed upon the shaft and in sliding contact with the walls and partitions of the casing to cover the ap-

ertures thereof, a fixed flexible stud-shaft having a journal-box at its free end for receiving one end of the shaft, 16, a power-transmitting shaft, 16^a, journaled in fixed boxes, and a universal joint connecting abutting ends of shafts 16 and 16^a. 15

In testimony whereof I affix my signature in presence of two witnesses.

ERIK S. HAGEN.
